UNITED STATES PATENT OFFICE.

IRVING W. FARQUHARSON, OF MEDIA, PENNSYLVANIA.

SPARK PLUG.

Application filed January 24, 1925. Serial No. 4,413.

This invention relates to a spark-plug as used in the cylinders of internal combustion engines.

The use of spark-plugs in an engine of the above mentioned type is attended by an accumulation of lubricant, soot or carbon, and other foreign matter, to such an extent as to result in short circuiting the current or to the production of a bridge across the arc gap between the terminals, thus precluding the formation of a spark, interfering with the operation of the engine, and requiring the operator to remove, clean and replace the plug.

One object of this invention is to overcome the foregoing, and other, objections, and to produce a simple, efficient, and economical construction wherein the accumulation of foreign matter is minimized so as to obviate the production of a short circuit.

Another object resides in the provision of general details of construction and arrangement and combination of parts for attaining the results sought by the foregoing object.

Another object is to provide a structure in which oil accumulating pockets are avoided in the plug bushing.

A still further object is to provide a structure in which a relatively short bushing but a relatively long core and its supplemental electrode is provided in order that the electrode may project well into the explosion chamber of an internal combustion engine to obtain sparking as near the center of the compressed charge as possible. By constructing a spark-plug to attain the above objects I am enabled to effect a saving in both metal employed in the bushing and in time consumed in making the bushing. Other and further objects not at this time more particularly referred to will appear hereinafter.

The invention consists of the novel construction hereinafter described and finally claimed.

The nature, characteristic features and scope of the invention will be more fully understood from the following description taken in connection with the drawings forming part hereof, and in which:

Fig. 1, is a view in elevation of the spark plug; and

Fig. 2, is a central longitudinal sectional view of Fig. 1.

For the purpose of illustrating my inven-

tion I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawing in detail, the reference numeral 1, designates a metal bushing which is relatively short in length as compared with those now in use and is externally screw-threaded at one end as at 2, for a portion of its extent, in order that it may be screwed into the cylinder of an internal combustion engine, the opposite end being squared as at 3 for tool accommodation. The bushing at its inner end is provided with an annular plane surface 4, in contradistinction to the usual annular recessed portion commonly employed. Extended through the bushing is a core 5 of porcelain, mica, lava or equivalent material provided with an electrode 6. The core is cylindrical throughout the major portion of its extent and is provided with a shoulder 7 which abuts against the annular seat 8 with the bushing 1, and is clamped to place by means of gland 9. That end of the core 5 which is for penetration of a cylinder or ignition chamber is relatively long as compared to cores now in use and gradually tapers cone-fashion so that its cross-sectional area gradually reduces as it nears the sparking point 10 of the electrode. The core, at that portion thereof, immediately adjacent the annular surface 4 of the bushing or the juncture of the cylindrical and tapered parts is provided with an annular raised portion, as at 11 to prevent an oil collecting pocket at this place. Carried by the inner end of the bushing is a second electrode 12 arranged in parallelism with electrode 6, its terminal being bent laterally toward the sparking point 10 to form a sparking foot 13. The object of this construction is to avoid any semblance of a shell or housing around the core as in common use and which collect oil vapors from the oil feed of the engine and as the flash of the explosion can not reach into this shell or housing, the oil deposits are baked to a carbon which causes

a short circuit of the ignition current and it fails to do its work. By experiment I have proven, when a spark-plug is constructed, as shown, without housing or shell covering 5 core, that the oil does not collect around the core in sufficient quantities to resist the explosion flashes, but is burned off at each firing of the gases. The relative distance between the core and electrode 12 must be very 10 carefully placed to avoid possible oil pockets. A further benefit is derived by having the core project well into the explosion chamber to get the spark as near the center of the compressed charges as possible, with 15 the attending results that the flash passes from the center to the outside, whereas in the other methods, the flash is started on the extreme outside and has to pass clear across the entire charge, with the result of 20 considerable waste of gas at each explosion. Thus I obviate the use of the Dule double ignition with the necessary use of two spark-plugs. It is however obvious that the length of the core and electrode 12 must be 25 controlled according to the construction of the particular engine in which used, but under no condition are these two parts to be covered by shell, housing or covering, of 30 any description, either in part or whole, singly or together, as the avoiding of oil pockets is the main and fundamental principle of this invention. I wish further to set forth that in constructing a spark-plug as shown, there is a saving of about $\frac{1}{3}$ of the 35 metal and $\frac{1}{2}$ of the labor used in the standard plugs on the market.

It will now be apparent that I have devised a novel and useful construction which embodies the features of advantage enumerated 40 as desirable in the statement of the invention and the above description and while I have in the present instance shown and described the preferred embodiment thereof which has been found in practice to give 45 satisfactory and reliable results, it is to be understood that the same is susceptible of modification in various particulars without departing from the spirit or scope of the

invention or sacrificing any of its advantages.

50

Having thus described my invention what I claim as new and desire to secure by Letters Patent, is:

1. In a spark plug, a bushing the inner 55 end of which has an unflanged, plane annular surface, an insulator core having an electrode therein carried by said bushing, a portion of said core being cylindrical and the major portion tapering at its inner end, and being exposed throughout said major portion, the juncture of said cylindrical and tapered parts forming a raised annular part 60 11 which is positioned immediately adjacent said bushing and said tapered part of the insulator core being at least twice the length 65 of said bushing, and an additional electrode carried by the bushing the major portion of which parallels the tapered part of the core electrode and is of substantially the same length as said tapered part, the terminal of 70 which is bent laterally at right angles toward the sparking point of the core electrode, but which does not extend therebeyond.

2. In a spark plug, a bushing having an 75 unflanged inner end and an insulator core carried therein, an electrode passing through and movably positioned within the core, a portion of said core being cylindrical and the major portion tapering at its inner end 80 and protruding beyond the bushing, said major portion being exposed throughout and forming with said cylindrical portion a raised annular part positioned immediately adjacent said end of the bushing, an additional electrode carried by the bushing, the major portion of which parallels the tapered part of the core electrode and is of substantially the same length as the tapered part of 85 said core electrode, said additional electrode being bent laterally at right angles to the 90 sparking point of the core electrode.

In testimony whereof, I have hereunto signed my name.

IRVING W. FARQUHARSON.
